UNITED STATES PATENT OFFICE.

FREDERICK SEDGWICK, OF CHICAGO, ILLINOIS.

ELECTRICAL MECHANISM FOR OPERATING SAFE BOLT-WORK.

SPECIFICATION forming part of Letters Patent No. 329,222, dated October 27, 1885.

Application filed March 10, 1885. Serial No. 153,307. (No model.)

To all whom it may concern:

Be it known that I, FREDERICK SEDGWICK, of Chicago, in the county of Cook and State of Illinois, have invented certain new and useful Improvements in Electrical Mechanism for Operating Safe Bolt-Work, of which the following is a description, reference being had to the accompanying drawings, in which—

Figure 1 is a longitudinal vertical sectional view of said device as viewed from the rear, together with a portion of the usual safe bolt-work. Fig. 2 is a vertical sectional view of a safe-door, showing said mechanism applied thereto. Fig. 3 is a horizontal sectional view in detail on the line xx , Fig. 1; and Fig. 4 is a modification in detail of the construction shown in Figs. 1 and 3.

Like letters of reference indicate like parts in the different figures.

20 The object of my invention is to provide a mechanism whereby the bolt-work of safes and vaults may be thrown or retracted by means of compressed air acting upon a suitable piston, diaphragm, or other equivalent device connected with the bolt-work, said compressed air being liberated to act upon said mechanism intended to be directly actuated thereby by means of a suitable valve operated by one or more electro-magnets having electrical connections with the outside of the safe, from whence and by which said mechanism may be manipulated, substantially in the manner hereinafter more particularly described and claimed.

35 In the drawings, A represents an air-tight compartment or case constructed from brass or other suitable material, and attached to the inside of the safe-door B, Fig. 2, by means of bolts or screws. A plate or cap, a, screwed to said case and having an air-tight or hermetically sealed joint, may serve to give access to the interior of said compartment.

40 Preferably within, so as to make the same more compact in form, I place a cylinder, C, which, with the piston c, rod c', hand-lever c'', pivotally connected by means of the link c', as shown, to the stud c'', cast or otherwise attached to said case, forms an air-pump, said cylinder having a cap, c'', at the top, to serve as a guide for the piston-rod, an opening, c'', being made therein for the admission of air, and said cylinder and piston respectively

being provided with valves c' c'', adjusted, as shown, so that the movement up and down of the lever c'' serves to compress a volume of air 55 into the compartment A. Preferably within said case I also place a cylinder, D, provided with a piston, d, having piston-rod d', which passes through the end of said cylinder and the wall of the case A, (to which said cylinder is attached,) the opposite end of said piston-rod being rigidly connected with the usual bolt-bar, E. Said cylinder is provided with ports d'' d'', communicating with the compartment A, which are opened and closed by 60 means of a two-way cock or valve, F, having ports f f', so placed that a partial revolution of said valve serves to open one port while the other is closed. A notch, f'', in said valve likewise serves to connect the ports with an 65 exhaust-pipe, f'', Figs. 1 and 3, leading to the outside of the case A.

Rigidly connected with the axis of the valve F are cross-bars f f', to which are attached armatures G G' in suitable proximity to the 75 poles of electro-magnets H H' to be attracted thereby. Wires h h' are connected with said magnets, respectively, and with binding-posts J J', secured to the case A, from which posts wires h h' are carried through the door of the 80 safe, as clearly shown in Fig. 2, and connected with the usual push-buttons, K K', which are in turn connected by wires k k' to a battery-cup, L, the circuit-wire k'' of which connects with a binding-post, L', having metallic contact 85 with the safe-door B, as shown in said Fig. 2. The terminal wires h'' h'', Fig. 1, of said magnets are also connected with the case A by a screw, h'', thus completing the electrical circuit through the body of the door B with one 90 or the other of said magnets and the battery by means of the button with which said magnet is connected.

The operation of said mechanism is as follows: Assuming the safe-door to be open, the 95 operator first works the air-pump, thus compressing a volume of air within the compartment A. The door is then closed, and by pressing the button K' the magnet H' is excited and attracts the armature G', thus opening the port d'' and admitting the compressed air confined in the case A to the back of the piston D, thereby forcing the latter forward and throwing the bolt-work, as indicated.

Upon pressing the button K the operation is reversed, the armature G being attracted, thus rotating the valve F, while the compressed air behind the piston D is released through the pipe f⁵, which permits a backward movement of the piston. Hence so long as a volume of air is compressed within the compartment A the alternate pressure upon the buttons K K', as described, will throw or retract said bolt-work at will. When the safe is closed and the bolt-work thrown, it may be blocked by means of any well-known obstruction mechanism, and retained in place or released by a suitable lock.

15 It is obvious that instead of employing two magnets for operating the valve F a single magnet may be used to move the same in one direction—as, for example, H', Fig. 4—while a wire spring, H², may be employed to reverse said movement, which mechanism I regard as an inferior equivalent of the construction above described.

Having thus described my invention, what I claim as new is—

25 1. An electrical mechanism for operating safe bolt-work, consisting of an air-chamber provided with means, substantially as described, for compressing air therein, a valve for alternately admitting said air behind or in front of a piston within a suitable cylinder, the rod of which piston is connected with the bolt-work, an armature connected with said valve and in position to be attracted by electro-magnets having electrical connections with a circuit-breaking mechanism without the safe, and a battery-cup, whereby said magnets may be alternately excited, substantially as and for the purposes specified.

30 2. An electrical mechanism for operating

safe bolt-work provided with one or more electro-magnets having electrical connections with a circuit-breaker outside of the safe, a battery-cup, and an armature within the safe in electrical proximity to said magnet, by the movement of which armature a valve may be actuated, whereby a volume of compressed air is admitted from a suitable receptacle to a cylinder having a piston connected with the bolt-work, substantially as described, and for the purposes set forth.

40

3. The combination, with the usual multiple safe bolt-work, of an air-chamber arranged within the safe, with means for compressing air therein, a cylinder communicating with said chamber, the piston of which is connected with the bolt-work, electro-magnets having electrical connections with the outside of the safe, a circuit-breaker and battery-cup, and an armature connected with the cylinder-valve, whereby the excitement of one or the other of said magnets may serve to operate said valve and admit the air to said piston, substantially as described.

50

4. The combination, with the usual safe bolt-work, of an air-chamber, A, an air-pump, and a cylinder, B, the piston of which is connected with said bolt-work, said cylinder having communication with said chamber by means of ports which are alternately opened and closed by a valve actuated by one or more armatures and electro-magnets having electrical connections with a battery-cup and a circuit-breaking mechanism outside of the safe, substantially as described, and for the purposes specified.
